TELESCOPIC PROTECTOR

Samuel S. Roberts, Pittsburgh, Pa.

Application February 12, 1946, Serial No. 647,051

12 Claims. (Cl. 74—608)

1

This invention relates to a telescopic protector for traversing screws and the like and is particularly adapted for protecting the screw-downs of rolling mills against abrasive dirt and scale which are incidental to rolling operations. Various types of these devices are in use, such as disclosed in my Patent No. 2,061,331, dated November 17, 1936, but they all have various drawbacks. For example, my previous protector could not be successfully used in a horizontal position and, in addition, its parts sometimes became separated in hard usage.

It is an object of my invention to provide a telescopic protector which is non-separable, rigid, and has positive action in either direction.

Another object is to provide such a protector which is provided with a seal which can be removed and renewed without dismantling the protector.

A still further object is to provide a protector which can be used in a horizontal position.

These and other objects will be more apparent after referring to the following specification and attached drawings, in which:

Figure 1 is a view, partly in section, of my protector in place on a vertical screw-down of a rolling mill;

Figure 2 is a view taken on the line II—II of Figure 1;

Figure 3 is a view taken on the line III—III of Figure 1;

Figure 4 is a sectional view taken on the line IV—IV of Figure 2 and showing the protector in nested position;

Figure 5 is a sectional view of my protector when used in a horizontal position;

Figure 6 is a view taken on the line VI—VI of Figure 5;

Figure 7 is an enlarged sectional view taken on the line VII—VII of Figure 8;

Figure 8 is an enlarged detail of a modification;

Figure 9 is a view of the spring used in Figure 7;

Figure 10 is an enlarged view, partly in section, of a modification; and

Figure 11 is a view, partly in section, of a further modification.

Referring more particularly to the drawings, Figures 1 to 4 disclose my protector as applied to a vertical screw-down. The reference numeral 2 indicates the roll housing which has a housing nut 4 mounted therein. A screw 6 passes through the nut 4 and engages the roll bearing chuck 8 which supports the roll 10. The protector boot 12 of my invention surrounds the screw 6 and

extends between the housing 2 and the chuck 8. The boot 12 is made of a plurality of individual rings 13, 14 and 15 which increase in width and decrease in diameter from one end of the protector 5 to the other end. As shown the ring having the maximum diameter and minimum width or height is at the top. The construction of the protector 12 is the same regardless of whether it is used in a vertical or horizontal position and the details are best shown in Figures 5 and 10. The top ring 14 is provided with an outwardly extending flange 16 at its upper end to which is fastened an outwardly extending annular anchorage plate 18 having a plurality of holes 20 therein. An annulus 22, having a substantially square cross section, is welded to the inside portion of the overlapping end of the upper ring 14. The bottom ring 13 and intermediate rings 15 are provided with outwardly extending flanges 24 at their lower or overlapping ends. Welded to the inside of the overlapping end of each of the rings 15 is an annulus 22 identical with the one welded to the top ring 14. An annulus 26, similar to the annulus 22, is welded to the top outside surface of each of the rings 13 and 15. The corners of the annuli 22 and 26 opposite the weld are rounded to provide flexibility in the protector boot 12. The annuli 22 and 26 form inwardly extending flanges on the overlapping end and outwardly extending flanges on the underlapping end of the rings with the length of the flanges being substantially equal to one-half the difference between the inside diameter of the overlapping ring and the outside diameter of the underlapping ring. An annular anchorage plate 28 having a plurality of holes 30 therein is welded to the flange 24 of the bottom ring 13. The top anchorage plate 18 is fastened to the housing 2 by means of cap screws 32 and the bottom annular anchorage plate 28 is fastened to the chuck 8 by means of cap screws 34. As the screw 6 is raised or lowered, it moves the chuck 8 with respect to the housing 2 and the telescoping rings 13, 14 and 15 are positively moved with respect to one another regardless of the direction of movement because of the positive connection with the housing 2 and chuck 8. The increase in width of the rings as they decrease in diameter is approximately an amount equal to the thickness of the flange 24 so that the rings are closely nested in retracted position, as shown in Figure 4. Thus, it is possible to obtain greater travel with the same closure. As shown in Figures 2 and 4, 50 a plurality of spaced apart downwardly extend-

ing lugs 36 may be welded to the ring 18. L-shaped lugs 38, spaced apart in the same manner as lugs 36, are welded to the lower plate 28. When it is desired to keep the protector boot 12 in retracted position, such as when removing the chuck 8, the screws 34 are removed and the adjusting screw 6 raised to its top position. Pins 40 are then placed in matching holes in the lugs 36 and 38 to hold the protector 12 in the retracted position shown in Figure 4.

It is often desirable to have an oil-tight dust proof enclosure around the adjusting screw. Figures 7, 8 and 9 disclose a modification for making the protector 12 oil-tight and dust proof. In this construction the annulus 22 is replaced by a triangular annulus 42 having its bevelled face extending inwardly away from flange 24. A split packing ring 44, having a triangular shape complementary to that of the annulus 42, is placed in the opening between the annulus 42 and the ring 14. A ring follower 46 is placed on the packing ring 44. Self-take-up of the sealing ring 44, to compensate for wear, is accomplished by inserting flat curved springs 48 between the ring follower 46 and anchorage clips 50, which are arranged around the periphery of the protector at spaced intervals. The clips 50, which are channel-shaped and have one leg shorter than the other, are slipped over the flanges 24 with the short leg beneath the flange and the long leg extending over the packing ring 44. Pin punch prick marks 52 fix the clips to the flange 24 and the springs 48 to the clips 50. The springs 48 exert constant pressure on the packing, thus causing the packing ring to slide inwardly over the inclined surface of the annulus 42.

The installation of the protector boot 12 in a horizontal position is shown in Figures 5 and 10. The construction of this boot is the same as that of the vertical boot and the same reference characters are used to designate the parts thereof. As shown in Figure 5, the rings 15 are maintained in their vertical position by means of counterpoise arms 54 welded to the flanges 24. The arms 54 are provided with two vertical portions connected by a horizontal portion as shown. The horizontal portions of the arms gradually decrease in diameter from the ring of smallest diameter so that they will fold in the closure space. The second vertical portion of the arm is approximately above the center of its ring 15. Attached to the top of this arm is a spring 56 which is suspended to the panel pivot of a pantograph 58, which is attached to the relatively movable parts 60 and 62. At the parts 60 and 62 move together the parts of the pantograph and the rings of the protector 12 move toward their collapsed position with the rings and the pantograph substantially maintaining their position with respect to one another. The springs 56 provide flexibility between the ring sections 15 and the pantograph 58 as the boot 12 contracts and expands, thus preventing binding during movement of the boot. In case no space is available for an overhead mounting, an underslung folding gate provided with compression instead of extension springs may be used to provide the moving support for the arms 54.

In place of the pantograph 58 and springs 56, a guide rod 64 may be fastened between the supports 60 and 62. This construction is only possible when one of the parts 60 and 62 has an opening therein through which the rod 64 can slide. As shown in Figure 10, the rod 64 is rigidly connected to part 60 and slides through an open-

ing in part 62. The arms 54, instead of being fastened to a spring 56, are provided with brackets 66 at their outer ends. The brackets are provided with openings having the same shape as bar 64 and as the parts 60 and 62 are moved together, the arms 54 slide over the rod 64.

When it is desired to protect a horizontal shaft or plunger 70 (Fig. 11) instead of a screw, the arms 54 and flanges 24 may be omitted and replaced by guide rings 72 fastened to the inside of the underlapping ends of the rings 15 adjacent the annulus 26. The guide rings 72 are provided with openings of approximately the same size as the shaft 70 being protected so that the shaft 15 acts as a support to maintain the rings 13, 14 and 15 in their vertical position while the rings slide thereover.

While several embodiments of my invention have been shown and described it will be apparent that other adaptations and modifications may be made without departing from the scope of the following claims.

I claim:

1. A telescopic protector for traversing screws and the like comprising a plurality of overlapping rings, an inwardly extending flange on the overlapping end of each ring, an outwardly extending flange on the underlapping end of each ring, the length of said flanges being substantially equal to one-half the difference between the inside diameter of the overlapping ring and the outside diameter of the underlapping ring, the flange on the overlapping end being shaped to provide a chamber between it and the underlapping end, said chamber being open to the outside of the protector, packing in said opening, an outwardly extending flange on the overlapping end of each of the rings except the one having the largest diameter, and separable means fastened to the last named flange for holding the packing in place.

2. A telescopic protector for traversing screws and the like comprising a plurality of overlapping rings, an inwardly extending flange on the overlapping end of each ring, an outwardly extending flange on the underlapping end of each ring, the length of said flanges being substantially equal to one-half the difference between the inside diameter of the overlapping ring and the outside diameter of the underlapping ring, the flange on the overlapping end having a beveled inner face, a packing ring having a complementary beveled outer face located in the opening between the underlapping end and the beveled inner face of the flange, an outwardly extending flange on the overlapping end of each of the rings except the one having the largest diameter, and means fastened to the last named flange for holding the packing in place.

3. A telescopic protector for traversing screws and the like comprising a plurality of overlapping rings which progressively decrease in diameter from one end to the other, an inwardly extending flange on the overlapping end of each ring, an outwardly extending flange on the underlapping end of each ring, the length of said flanges being substantially equal to one-half the difference between the inside diameter of the overlapping ring and the outside diameter of the underlapping ring, and an outwardly extending flange on the overlapping end of each of the smaller diameter rings, said last named flange cooperating with the other flanges to prevent over-riding of the ring sections, each of said rings being wider than the larger diameter ring adja-

cent thereto an amount substantially equal to the thickness of the last named flange.

4. A horizontal telescopic protector for traversing screws and the like comprising a plurality of overlapping rings which progressively decrease in diameter from one end to the other, counterpoised arms connected to the overlapping end of at least some of the intermediate rings, each of said arms having a horizontal portion between oppositely extending vertical portions, the distance of the horizontal portions from the centerline of the protector decreasing from the smallest diameter ring to the largest diameter ring so that the horizontal portions will fold into one another, a horizontal support, and means for connecting the outer vertical portions of said arms to the support.

5. A horizontal telescopic protector for traversing screws and the like comprising a plurality of overlapping rings which progressively decrease in diameter from one end to the other, an inwardly extending flange on the overlapping end of each ring, an outwardly extending flange on the underlapping end of each ring, the length of said flanges being substantially equal to one-half the difference between the inside diameter of the overlapping ring and the outside diameter of the underlapping ring, an outwardly extending flange on the overlapping end of each of the smaller diameter rings, counterpoised arms connected to at least some of the last named flanges, each of said arms having a horizontal portion between oppositely extending vertical portions, the distance of the horizontal portions from the centerline of the protector decreasing from the smallest diameter ring to the largest diameter ring so that the horizontal portions will fold into one another, a horizontal support and means for connecting the outer vertical portions of said arms to the support.

6. A horizontal telescopic protector for traversing screws and the like extending between relatively movable parts comprising a plurality of overlapping rings which progressively decrease in diameter from one end to the other, counterpoised arms connected to the overlapping end of at least some of the intermediate rings, each of said arms having a horizontal portion between oppositely extending vertical portions, the distance of the horizontal portion from the centerline of the protector decreasing from the smallest diameter ring to the largest diameter ring so that the horizontal portions will fold into one another, a pantograph having its opposite ends attached to the relatively movable supports, and a spring for connecting the outer vertical portion of each arm to one of the panel pivots of the pantograph.

7. A horizontal telescopic protector for traversing screws and the like extending between relatively movable parts comprising a plurality of overlapping rings which progressively decrease in diameter from one end to the other, an inwardly extending flange on the overlapping end of each ring, an outwardly extending flange on the underlapping end of each ring, the length of said flanges being substantially equal to one-half the difference between the inside diameter of the overlapping ring and the outside diameter of the underlapping ring, an outwardly extending flange on the overlapping end of each of the smaller diameter rings, counterpoised arms connected to the overlapping end of at least some of the last named flanges, each of said arms having a horizontal portion between oppositely extending vertical portions, the distance of the horizontal por-

tions from the centerline of the rings decreasing from the smallest diameter ring to the largest diameter ring so that the horizontal portions will fold into one another, a pantograph having its opposite ends attached to the relatively movable supports, and a spring for connecting the outer vertical portion of each arm to one of the panel pivots of the pantograph.

8. A horizontal telescopic protector for traversing screws and the like extending between relatively movable parts comprising a plurality of overlapping rings which progressively decrease in diameter from one end to the other, counterpoised arms connected to the overlapping end of at least some of the intermediate rings, each of said arms having a horizontal portion between oppositely extending vertical portions, the distance of the horizontal portions from the centerline of the rings decreasing from the smallest diameter ring to the largest diameter ring so that the horizontal portions will fold into one another, a horizontal bar having one end rigidly attached to one of the relatively movable parts and the other end slidably mounted in the other of said movable parts, and a bracket connected to the outer vertical portion of each arm, each of said brackets having an opening therein for slidably receiving said bar.

9. A horizontal telescopic protector for traversing screws and the like extending between relatively movable parts comprising a plurality of overlapping rings which progressively decrease in diameter from one end to the other, an inwardly extending flange on the overlapping end of each ring, an outwardly extending flange on the underlapping end of each ring, the length of said flanges being substantially equal to one-half the difference between the inside diameter of the overlapping ring and the outside diameter of the underlapping ring, an outwardly extending flange on the overlapping end of each of the smaller diameter rings, counterpoised arms connected to the overlapping end of at least some of the last named flanges, each of said arms having a horizontal portion between oppositely extending vertical portions, the distance of the horizontal portions from the centerline of the rings decreasing from the smallest diameter ring to the largest diameter ring so that the horizontal portions will fold into one another, a horizontal bar having one end rigidly attached to one of the relatively movable parts and the other end slidably mounted in the other of said movable parts, and a bracket connected to the outer vertical portion of each arm, each of said brackets having an opening therein for slidably receiving said bar.

10. A horizontal telescopic protector for traversing screws and the like comprising a plurality of overlapping rings which progressively decrease in diameter from one end to the other, a horizontal support and means connected to at least some of the intermediate rings and to the horizontal support for maintaining the rings in their vertical position.

11. A telescopic protector for traversing screws and the like comprising a plurality of overlapping rings, an inwardly extending annulus welded to the overlapping end of each ring, an outwardly extending annulus welded to the underlapping end of each ring, the annuli having an outside diameter substantially equal to the inside diameter of the overlapping ring and an inside diameter substantially equal to the outside diameter of the underlapping ring, and an outwardly extending flange on the overlapping end of each of

the smaller diameter rings, said last named flange cooperating with the said annuli to prevent over-riding of the ring sections.

12. A telescopic protector for traversing screws and the like comprising a plurality of overlapping rings which progressively decrease in diameter from one end to the other, an inwardly extending flange on the overlapping end of each ring, an outwardly extending flange on the underlapping end of each ring, the length of said flanges being substantially equal to one-half the difference between the inside diameter of the overlapping ring and the outside diameter of the underlapping ring, and an outwardly extending flange on the overlapping end of each of the smaller diameter

rings, said last named flange cooperating with the other flanges to prevent over-riding of the ring sections.

SAMUEL S. ROBERTS.
